(57) **CLAIM**

Having described my invention, I claim the ornamental design for a golf ball rake/claw retrieval apparatus, as shown and described.

DESCRIPTION

FIG. 1 is an elevational view of the present invention;

FIG. 2 is a left end view of FIG. 1;

FIG. 3 is a right end view of FIG. 1;

FIG. 4 is a front elevational view of FIG. 1;

FIG. 5 is an elevational view of a second embodiment of the invention of disclosed in FIG. 1; the rake is disclosed in an alternate position;

FIG. 6 is a left end view of FIG. 5;

FIG. 7 is a front elevational view of FIG. 5;

FIG. 8 is a reduced elevational view of FIG. 1; the broken line showing of a is for illustrative purposes only and forms no part of the claimed design; and,

FIG. 9 is an enlarged elevational view of FIG. 8.
